WRAPPING MACHINE UNIT

Clarence J. Malhot, Oak Park, Ill., assignor to
 F. B. Redington Co., Chicago, Ill., a corpora-
 tion of Illinois

Application November 4, 1936, Serial No. 109,196

10 Claims. (CL 93—2)

This invention relates to machines of the type commonly employed for wrapping packages and particularly to a unit for wrapping machines of that type. More specifically, the invention relates to a unit adapted to be incorporated in a wrapping machine which seals the wrapper about a package.

An important object of the invention is to provide a new and novel device for positively sealing a package to make it moisture proof and to prevent leaking of the package by the employment of means adapted to engage the flaps or seams to be sealed of a package and maintain a predetermined temperature so as to prevent the wax or other adhesive used from cooling too rapidly and thereby inhibit the proper feeding action of the package and, in some instance, even causing tearing of the package.

Another object of the invention is to provide a sealing element which is provided with a water circulating system to maintain the elements at the proper temperature to prevent the adhesive on the package from cooling too rapidly, and further to prevent the wax or adhesive from sticking to the element whereby the wrapped package to be sealed always remains free of the wax or adhesive, insuring that the package will freely and readily move to discharging position.

A further object of the invention is to provide a plurality of elements located in a predetermined position and operating in a predetermined manner so as to positively cause a tight seal to be made on the package without cooling the sealed seams and laps too rapidly, thereby overcoming the possibility of the wax sticking to and caking up the element.

Numerous other objects and advantages will be apparent throughout the progress of the following specification.

The accompanying drawings illustrate a selected embodiment of the invention, and the views therein are as follows:

Fig. 1 is a detail elevational view, partly in section, of a wrapping machine unit and having the invention applied thereto.

Fig. 2 is a detail transverse sectional view on the line 2—2 of Fig. 1.

Fig. 3 is a detail vertical sectional view on the line 3—3 of Fig. 1.

Fig. 4 is a detail sectional view taken on the lines 4—4 of Figs. 1 and 3.

Fig. 5 is a detail vertical sectional view through a modified form of element which can be substituted for the element shown in Figs. 1 to 4.

Fig. 6 is a detail perspective view of one form

of package in connection with which the invention is described.

Fig. 7 is a view of the converse side of the package.

Fig. 8 is a detail perspective view of a package having a different form of wrapper thereabout, all the seams of the wrapper being on one side of the package.

Fig. 9 is a detail sectional view showing a modified form of heater block arrangement.

Fig. 10 is a view similar to Fig. 3, but showing a modified form of sealer element.

The type of machine with which the present unit is adaptable may be any conventional type of wrapping machine which includes a base upon which a conveyor 8 is rigidly mounted or supported. The conveyor 8 herein shown is in the form of a channel into which the upper reach 9 of a conveyor chain 10 is adapted to travel. The conveyor chain may be operated in any particular manner such as by a drive sprocket 11 arranged at one end of the conveyor, and the conveyor chain 10 may operate over an idler pulley 12 as shown in Fig. 1. The conveyor chain is provided with a plurality of spaced pusher lugs 13 which are adapted to engage a package and move it along continuously or intermittently in accordance with the manner in which the drive 11 operates. Instead of the particular conveyor chain shown any other kind of conveying, transporting or translating mechanism may be used with equal results.

The wrapping machine with which the present invention is particularly applicable is provided, with means (not shown) for folding a wrapper 14, Figs. 6 and 7, about a package 15 whereby the free edge of the wrapper or the lapped seam 16 thereof and the end flaps 17 and 18 are provided. The wrapping machine is also adapted to apply an adhesive of a particular kind and nature to the seam 16 and to the seams around and about the end flaps 17 and 18. The purpose of the invention primarily is to cause the package to be completely and tightly sealed to provide a moisture-proof package, and while the invention is adaptable for use in connection with various kinds of adhesives the present invention is described in connection with wax as the adhesive or binding agent.

After the wrapping machine has completed folding the wrapper 14 to provide a package 15 for the article to be wrapped and which wrapper is wrapped about the article, the edges and seams about the free edge and about the edges of the flaps 17 and 18 and possibly underneath the

edges and flaps are provided with a coating of wax. It is, of course, to be understood that instead of applying the wax to the wrapper the entire wrapper itself may be made of material 5 containing wax or equivalent adhesive whereby the wax is melted at a predetermined temperature to provide sealing contact with various parts of the package, particularly along the seams and free edges of the wrapper and flaps. It 10 suffices to say, therefore, that the wrapper being used has either wax or paraffin applied thereto, is wax or paraffin treated, or is a wrapper of the type which is commonly known as "waxed paper".

Heater devices 19, designated herein as heater 15 blocks, are arranged in a particular manner so that the package, when wrapped, will be carried by the conveyor chain 10 between the heater devices or blocks 19, Fig. 2. The heater devices or blocks 19 may comprise lower side blocks 20 and 20 21 mounted inwardly of the side edges 22 of the conveyor channel or guide 8. A channel-shaped guide or block 23 is arranged between the blocks 20 and 21 and is provided with an opening 24 through which the upper reach 9 of the conveyor chain 10 is free to pass. The blocks 20 and 25 21 are provided with recesses 25 and 26 into which the overhanging edges 27 and 28 on the upper heater block 29 are received.

The upper heater block 29 is provided with a 30 longitudinal groove or opening 30, Fig. 2, which is shaped to conform with the shape of the package to be sealed. The package 15 therefore has its bottom surface supported on the upper surfaces 31 of the blocks 20, 21 and 23. The side edges 35 and the top of the package are encased by the material of the heater block 29 which surrounds the longitudinal groove or recess 30. The package is urged along its path by a lug 13 on the chain 10, which lug extends a predetermined distance 40 above the said upper surfaces 31. The block 29 has fixed thereto upstanding pins or bars 32 which extend through proper supports 33 carried by a part 34 of the wrapping machine frame. Springs 35 are arranged between the upper 45 surfaces of the block 29 and the lower surfaces of the member 34 and thereby tend to urge the block 29 downwardly. The block 29 is therefore free to have vertical movement, the amount of vertical movement being determined or limited 50 by the washers or other stops 36. The package 15 as it passes through the heater devices or blocks 19 therefore rests upon and is urged against the upper surfaces of the lower elements 21, 22, 23 and the package is caused to bear firmly 55 against the surfaces 31 of these elements 20, 21 and 23. The wax or paraffin or other adhesive which is on the package 15 is caused to soften to the proper extent to permit a seal to be effected between the contacting parts of the wrapper.

60 Chilling or cooling elements have been arranged in close proximity to the heater blocks for the purpose of chilling or cooling the wax and causing it to set in the endeavor to form a tight seal. In actual practice it has been found that 65 such a cooling arrangement is impractical in many instances, because the cooling elements set the wax too quickly. Leaking or free wax was picked up by the cooling element and formed a rough coating thereon and on the package, and 70 inhibited the free movement of the package. Furthermore, the accumulation of this wax on the cooling elements, particularly where these elements engaged the package, package caused a rough or caked surface preventing a proper seal 75 and in many instances caused the seams to tear

and open before the wax was properly set. Another disadvantage in the cooling system was that the wax would become set so quickly that the wax would become lumpy or caked and form voids, preventing the accomplishment of a moisture-proof package. The present invention has been designed to obviate these inherent disadvantages, by providing an improved sealer element 37 located at a suitable position in the conveyor in advance of the heater devices 19.

The sealer element 37 comprises lower spaced blocks 38 and 39 and a central U-shaped block 40 which conform in shape to the previously describe blocks 20, 21 and 23, respectively, and are provided with the aforesaid surfaces 31 to properly support the lower surfaces of the package 15, Fig. 3. The blocks 38 and 39, however, are provided with longitudinal bores or passages 41 and are connected preferably at their bottoms with a pipe line 42, Fig. 3, there being vertical 20 bores or passages 43 provided therein to effect communication between the longitudinal passages 41 and the connecting pipe line or passage 42. The upper block 44 is substantially the same shape and contour as the previously described 25 heater block 29, but is provided with three longitudinal bores or passages 45, 46 and 47, Figs. 3 and 4. These passages are connected inwardly by end 30 passages 48, Fig. 4. A pipe line 49 connects the lower block 39 with one side of the upper block 44, there being a communicating passage 50 in the block 37 to form communication between the longitudinal opening 45 in the upper block and the pipe line 52. A feed pipe line 52 leads from a pump 53 to the upper block 44, there 35 being a communicating passage 54 in the block 37 to form communication between the longitudinal opening 45 in the upper block and the pipe line 52. A lower pipe line or discharge line 55 makes communication through the passage 56 40 with the opening 41 in the lower block 38, and this line 55 leads to a tank 57 in which water or other suitable liquid 58 is kept. A pipe line 59 connects the tank 57 to the pump 53, the pump 53 being driven in any suitable manner such as by an 45 electric motor. A heating element 60 is operatively arranged in the tank 57 to heat the water 58 to the desired temperature.

In the particular machine described, being of a predetermined size for a package of certain dimensions, it has been found that a temperature range from 110 degrees to 118 degrees Fahrenheit is the proper temperature to use because the device operates more advantageously when such temperature range is used for the specific purpose intended. Of course, in machines of a different size to accommodate a different or large package the temperature is varied to accommodate and suit the purpose intended. Too, the kind of wax, paraffin or other adhesive used will 60 vary the temperature accordingly. A thermostatic control element such as an aquastat 61, Fig. 3, is provided to control the operation of the heating element 60 to keep the water in the tank 57 somewhere between the desired temperatures. 65 The circulating water, therefore, is maintained at the proper temperature and is pumped by the pump 53 through the line 52 into the block 37, passing through the passages 45, 46, 47, 48 and out through the line 49 into the lower block 38. 70 This water then flows through the passage 41 in the block 39 through the line 42, then through the passage 41 in the block 38, and out through the line 55 where it is again discharged into the tank 57.

The water is maintained at the proper temperature, which is preferably between 110 degrees and 118 degrees Fahrenheit for a machine of the present size, and is continually circulated throughout the sealer element. By keeping the sealer element at a predetermined temperature the flaps and seams of the wrapper have a chance to be compressed tightly against the companion parts of the wrapper and the cooling of the wax is slow or delayed, thereby preventing the formation of lumps and voids which would occur if the wax were set too quickly. Furthermore, by maintaining the heater elements at the predetermined temperature there is very little likelihood, if any, of the wax adhering to the surfaces of the sealing element, and even such wax which would stick to the sealing element would be soft enough to permit it to be rubbed off by the next succeeding package without in any way harming or tearing the wrapper. While it may seem that the water circulated through the sealing element would be heated by heat picked up by conduction from the heater element of the heater block 19, the sealer element cools by radiation and, therefore, it is not a matter of starting out with cold or cool water which becomes heated by operation because any heat in addition to the temperature of the water is thrown off by radiation and therefore dissipated. The arrangement is such that the water circulated throughout the sealer is constantly maintained at a temperature from about 110 degrees to 118 degrees Fahrenheit for the present machine.

The upper sealer block 37 is also supported on the member or bar 33, being resiliently mounted by means of the pins 32, springs 35 and elements 36 previously described in connection with the heater blocks.

For forming a seal of a package different than the package shown in Figs. 6 and 7, a different type of sealer may be employed. In Fig. 5 the sealer element comprises side blocks 62 and 63 and a central block 64 which conform generally to the previously described blocks 38, 39 and 40. The device is so constructed that the package 15', Fig. 5, rests on the upper surfaces of the central block 64 and has its end flaps 65 resting on top of the blocks 62 and 63. Upper blocks 66 and 67 are spring urged by the spring 35 against the bottom blocks 62 and 63 to provide the necessary pressure on the flaps. A central block 68 is adapted to rest on the package as shown. The blocks 62, 63, 66, 67 and 68 are provided with passages 69 and have proper communication in the manner similar to that shown in Fig. 3 for the sealer 31. Pins are provided to support the device on a part 10 of the frame.

Fig. 9 discloses a form of heater devices 19 which may be substituted for the heater devices shown in Fig. 2. These heater devices, Fig. 9, have the upper block 29 formed rectangular in cross section with a relatively straight lower package engaging surface 70', there being grooves 71 provided along the edges to accommodate the flaps 72 of a package 73, Fig. 8. The lower heater block, Fig. 9, has a straight package engaging surface 74 which is recessed into the top thereof, there being upstanding projections 75 at the side edges to engage and guide the package 73. This lower block, Fig. 9, is also provided with the opening 24 through which a transporting or translating device such as the specific conveyor chain 10 may operate.

The package 73, Fig. 8, is shown similar in size and shape to the package shown in Figs. 6 and 7

except the flaps 72 and the wrapper overlap 16 are all on the same side thereby providing all the seams 77 on one side of the wrapper. It is obvious that various shaped and sized packages may be used in connection with the present machine as all that is required is change in the block designs of the heater and sealer elements.

In Fig. 10, the sealer element 37 has its lower block 80 shaped like the lower block of the heater element shown in Fig. 8 to accommodate the package 73, Fig. 8. The upper block 44, Fig. 8, is similar to the upper block shown in Fig. 3 but has its bottom formed similar to the lower surface of the upper heater block shown in Fig. 9, and therefore may accommodate the package 73 shown in Fig. 8. The lower block 80, Fig. 10, is shown without fluid passages but if the same be desired it may be operatively hooked up with the fluid circulating system. However, where all the seams are on one side of the package as shown in Fig. 8, no circulating passages or system is required for the bottom block. A return line 81 is directly connected to the upper block 44, Fig. 10, and discharges into the tank 57.

The invention provides a novel unit for positively causing the proper sealing of a package whereby a moisture-proof package is attained.

Changes may be made in the form, construction and arrangement of the parts without departing from the spirit of the invention or sacrificing any of its advantages, and the right is hereby reserved to make all such changes as fairly fall within the scope of the following claims.

The invention is hereby claimed as follows:

1. The combination with a wrapping machine having a channel-shaped support, of a conveyor chain operating in said support, a sealer element adjacent the conveyor, said sealer element comprising an upper member and a lower member, one of said members having a portion thereof forming a guide for said conveyor chain to permit a wrapped article to be moved between said members, and the other of said members having restricted movement to permit passage of the article, while at the same time pressing said article between said members, means connecting the members together, and means for passing a heated fluid through said upper member, said connection and said lower member.

2. A sealer element for wrapping machines comprising an upper member having a plurality of passages therein, a lower member including spaced elements each having a passage therein, a line communicating with the passage in said lower elements, another line having communication with the passage in the upper element and the passage in one of said lower elements, a second line having communication with one of said lower elements and said tank, another line leading from said tank to said upper element, and a pump interposed within said last named line.

3. A sealer element for wrapping machines comprising an upper member having a passage therein, a lower member including spaced elements each having a passage therein, a line communicating with the passage in said lower elements, another line having communication with the passage in the upper element and the passage in one of said lower elements, a second line having communication with one of said lower elements and said tank, another line leading from said tank to said upper element, a pump interposed within said last named line, a heater element adapted to heat the fluid in said supply

tank, and an aquastat controlling the operation of the heater element.

4. A method of sealing packages containing adhesive along the seams thereof, comprising heating said adhesive, conveying the packages to a sealing station, heating a fluid medium, circulating said heated fluid medium across said packages to prevent too rapid cooling of said adhesive, and sealing said packages.

5. The combination in a wrapping machine, of means for transporting a wrapped article, main and auxiliary spaced apart sealing members, said main member having a recess and the auxiliary member cooperating with said recessed main member to form a housing for closely encircling the wrapped article, said main member being constructed to receive part of the transporting means to permit the wrapped article to be moved between said main and auxiliary members and through the encircling housing formed thereby.

6. The combination in a wrapping machine, of means for transporting a wrapped article, spaced first and second sealing members, said first member being constructed to receive the transporting means and having a surface to support the wrapped article in its movement thereacross, the second member having restricted movement to permit the passage of the wrapped article between said sealing members, and means operatively engaging said second sealing member for causing said second member to apply a force to the wrapped article supported on the first member to effectively press and seal the wrapper about the article.

7. The combination in a wrapping machine, of means for transporting a wrapped article, and means for sealing the wrapper about the article, said means comprising spaced upper and lower sealing members, said lower member including a central block and a pair of end blocks located on opposite sides of the central block, said end blocks supporting the ends of the wrapper to be sealed and said central block supporting the body of the wrapper and the article therein, the upper sealing member cooperating with said lower blocks to form a chamber to receive the wrapped article, and means for maintaining said upper sealing member and said end blocks at a predetermined temperature for sealing the wrapper about the article.

8. The combination in a wrapping machine, of means for transporting a wrapped article, and means for sealing the wrapper about the article, said means comprising spaced main and auxil-

iary sealing members, said main member including a central block and a pair of end blocks located on opposite sides of the central block, said end blocks supporting the ends of the wrapper to be sealed and said central block supporting the body of the wrapper and the article therein, said auxiliary member cooperating with said blocks of the main member to form a chamber to receive the wrapped article, said auxiliary member and said end blocks of the main member each having a passage therein, and means for circulating a fluid medium at a predetermined temperature through said passage to seal the wrapper about the article.

9. The combination in a wrapping machine having means for transporting a wrapped article and means for sealing the wrapper about the article, said means comprising a main member including a plurality of sealing blocks lying in a common plane and providing a supporting surface to receive the wrapped article, and an auxiliary member including a sealing block in spaced relation to said main member and having outwardly extending flanges at the side margins thereof, certain of the blocks of the main member having notches to receive said flanges whereby all of said sealing blocks cooperate to form a sealing chamber for receiving the wrapped article, one of said sealing blocks of the main member being provided with a guideway to receive a portion of the transporting means to permit the wrapped article to be moved through said sealing chamber.

10. The combination in a wrapping machine having means for transporting a wrapped article and means for sealing the wrapper about the article, said means comprising a main member including a plurality of sealing blocks lying in a common plane and providing a supporting surface to receive the wrapped article, and an auxiliary member including a sealing block in spaced relation to said main member and having outwardly extending flanges at the side margins thereof, certain of the sealing blocks of the main member having notches to receive said flanges whereby all of said sealing blocks cooperate to form a sealing chamber for receiving the wrapped article, one of said sealing blocks of the main member being provided with a guideway to receive a portion of the transporting means to permit the wrapped article to be moved through said sealing chamber, and means for maintaining certain of said blocks at a predetermined sealing temperature.

CLARENCE J. MALHIOT.
